METHOD OF AND ATTACHMENT FOR RUNNING-ON KNITTED FABRICS

Application filed May 14, 1930. Serial No. 452,303.

This invention relates to method of and attachment or mechanism for running-on knitted fabrics, and especially hosiery.

In order that the principle of the invention may be readily understood, we have disclosed in the accompanying drawings one embodiment of means constituting such attachment or mechanism, and the best mode known to use for practising the method of our invention and producing the resulting fabric structure.

In said drawings:

Fig. 1 is a right hand end elevation of a circular hosiery knitting machine having our invention applied thereto;

Fig. 1a is a view in elevation of the main pattern drum;

Fig. 2 is a front elevation of the head of said machine having our invention applied thereto;

Fig. 3 is a view of said machine partly in plan and partly in horizontal section on the line 3—3 of Fig. 2;

Fig. 4 is a vertical transverse section taken 25 through the needle cylinder and latch ring of said machine;

Fig. 5 is a detail in vertical section showing in feeding position the yarn guide or finger by which the yarns or threads for running-on, are delivered;

Fig. 6 is an inside elevation of part of the latch ring and representing the feeding of the two yarns or threads to the needles for running-on;

Fig. 7 is an enlarged view of the fabric structure at the running-on portion;

Fig. 8 is a diagram representing the feeding of the two yarns or threads to the needle during running-on; and

Fig. 9 is a further diagram showing a plurality of positions of a high needle and of a low needle.

The purpose of the invention is to start knitting upon bare needles. While the invention is shown as applied to a circular knitting machine having independent latch needles, it is evident that the invention may be practised upon many different types of knitting machines, whether circular or otherwise constructed, and with many different

structures of needles. Preferably the invention is practised with independent latch needles. We have chosen to illustrate the invention as applied to a circular hosiery machine of the well-known Banner type, as disclosed in the patent to Hemphill, No. 933, 55 443.

Obviously the invention may be applied to a plain hosiery machine, or to any type of machine whether for knitting hosiery or body fabric, or other material, but we have chosen to illustrate the same as applied to a machine wherein independently movable sinkers are employed which may be moved radially inward selectively at desired times according to some stitch variation or pattern, whether as a part of a plating operation involving the use of a plurality of knitting threads or whether but a single thread is to be supplied.

Referring more particularly to the drawings, the bed plate of the machine is represented at 1, the post usually employed in the Banner machine is indicated at 2, the cam carrier at 3, the needle cylinder at 4, and one of the narrowing pickers at 5. If the machine be for hosiery, preferably narrowing and widening pickers are employed in a manner not necessary to explain. The needles are desirably latch needles and the needles of the two respective groups are indicated in Figs. 6 and 8 at 6 and 7, needles of the groups 6 also being indicated at Fig. 4. The latch ring is indicated at 8, it being desirably of the usual pivoted character, and is provided with a mouth piece or opening 9 into which the several yarn guides (herein indicated generally at 10 as five in number) are moved in a manner well understood in the art, so that the proper yarn or thread (or plurality thereof, as for plating) may be fed at desired times, and yarn changes may be made in a manner not necessary to refer to in detail.

In practising our invention, we preferably proceed as follows:

The old stocking is dropped off and then a plurality of rotations of the needle cylinder (preferably four) are made without feeding any yarn or thread. We then make a certain division of the needles in a manner we will

now proceed to describe, and thereupon move in to feeding position a yarn finger 11, being (as shown) the first yarn finger of the group 10.

5 While the division of the needles may be effected in different ways, we preferably provide the following construction.

10 Under every other needle (namely, under the needles 6) we provide jacks 12 in the needle grooves, as shown most clearly in Fig. 4, and provide said jacks with suitable butts.

15 As herein shown, certain of the jacks (namely, those under the short butt needles) are provided with long butts 13 and the remainder of the jacks (namely, those under the long butt needles) are provided with short butts 14. This facilitates the in-movement of the jack cam hereinafter referred to. Means are provided to elevate the said jacks at the commencement of running-on so that the 20 fully elevated needles take both yarns and the needles which are not elevated by said jacks take only the lower yarn, being at a high enough level to do so.

25 Referring to Figs. 1 to 4 inclusive, there is desirably provided a stationary jack cam 15 which acts upon all the jacks to elevate them slightly but not enough to cause them to elevate the needles to take either yarn. 30 The purpose of said stationary jack cam 15 is to insure the bringing of all the jacks to the same level. Circumferentially beyond the stationary jack cam 15 is a movable jack cam 16 which (as here shown) is adapted to be movably radially of the needle cylinder by pattern controlled means. Herein for the purpose, said jack cam 16 is carried by a stem 35 slideable in a housing or bracket 17. Said jack stem is pivoted at 18 to a lever 19 itself pivoted at 20, so that in the movement of said lever the jack cam 16 is moved into and out of functioning relation to the jacks 12. At its outer end the lever 19 is pivotally connected at 21 to a link 22, a coil spring 23 suitably 40 connected to said lever and to said link being provided, tending to prevent any loose play in the connections. At its outer end said link 22 is pivotally connected at 23' to a bell crank lever 24 pivoted at 25 upon a bracket 26 on 45 the framing or bed plate. The coil spring 27 suitably connected to said bell crank lever 24 and to the framing tends to move said bell crank in a contraclockwise direction viewing Fig. 2.

50 The lower arm of said bell crank lever is pivotally connected at 28 to a downwardly extending link 29 which at its lower end (as illustrated in Fig. 1) is pivotally connected at 30 to one end of a lever 31 pivoted at 32 upon a bracket 33 attached to the framing. Said lever 31 bears at its inner end 34 upon a suitable cam 35 upon the usual pattern and stop motion member 36. Said cam 35 is of such length and is so positioned upon said wheel 36 that it causes the jack cam 16 to be

positioned under the jacks and remain there for the desired length of time, which is preferably a plurality of courses, and is specifically indicated in this embodiment of our invention as four courses, at the termination of which period the said jack cam 16 is withdrawn and the usual knitting is proceeded with, which may be plating or any other desired type of knitting.

70 We have stated that the jacks are placed under every other needle. Our invention is not limited in this respect, as said jacks may be placed under every other needle or every third needle or such other distributed needles as desired, so long as the principle of the 80 invention is adhered to.

At the same time that the jack cam 16 is moved radially inward, the yarn finger 11 is moved downward into feeding position,—that is, into the position shown in said Fig. 5. 85 Said yarn finger 11 is provided with two yarn or thread passages 37, 38 for feeding two yarns or threads A, B, respectively. The yarn A, as shown in Figs. 6 and 8, being 90 the upper yarn and the yarn B being the lower yarn. Desirably at the same time that the jack cam 16 is moved into functioning position, the front stitch cam 39 is moved out of functioning position, so that 95 none of the needles is raised by the front stitch cam, but the alternate needles are raised by the jack cam 16. The yarn B is fed at such a low point (namely, through the bottom of the yarn finger 11) that the needles not having jacks under them are nevertheless at a sufficiently high level to take the 100 yarn B.

Any suitable means may be provided to move the front stitch cam 39 into and out of functioning position. Herein we have represented in the following means.

105 As most clearly shown in Fig. 2, the front stitch cam 39 at its outer end is pivotally connected at 40 to a link 41 itself pivoted at 42 to the upper arm of the bell crank lever 43, 110 which is pivoted at 44 on the post or upright 2. To the lower arm of said bell crank lever 43 is pivotally connected at 45 an upright arm 46 which (as most clearly shown in Fig. 1) is pivotally connected at 47 to one arm of the 115 lever 48 pivoted at 49. The opposite arm of said lever 48 bears at its toe or end 50 upon a cam 51 of such length and so positioned 120 upon the regular pattern drum 52 (Fig. 1a) that the said front stitch cam 39 is out of functioning position during all the time that the jack cam is in functioning position, and is immediately thereafter restored to its usual position for knitting. In the disclosed 125 embodiment of the invention, the stitch cam period out of functioning position is for four courses, but it is to be understood that any other suitable number of courses may be the period during which the jack cam 16 is in 130

functioning position and the front stitch cam 39 is out of functioning position.

Assuming that the described positions last during the first four courses at the commencement of the knitting operation, the result is to produce the fabric shown in Fig. 7 and which we will now describe.

In Fig. 7, we have indicated the knitting of four courses for the running-on and one or 10 more courses thereafter, and have numbered these courses as first to fifth.

In the first course, as is evident from Figs. 6, 8 and 9, the needles that are raised by jacks thereunder (namely, alternate needles) take 15 both yarns A, B, and cast off the old loops. The needles that are without jacks thereunder take the lower yarn B only and are not raised high enough to cast off the old loops. This action is continued through three complete courses, as clearly indicated in Fig. 7, 20 so that the yarn A is floated back of the needles not having jacks thereunder. The yarn A is readily fed behind desired needles because the needles are forward hook needles, 25 as illustrated in Fig. 8. Upon the fourth course, as shown in Fig. 7, the yarns are cast off from those needles not having jacks thereunder, thus making tuck stitches, as shown in said figure. At the end of the fourth course 30 or such other number of courses as has been decided upon for the running-on operation, the yarn A is withdrawn from action. Thereupon knitting is continued in the usual manner. As shown in Fig. 7, another yarn 35 C is substituted for the withdrawn yarn A, and the two yarns C, B are fed in plating relation with preferably a greater tension upon one of the yarns than the other. Upon the conclusion of the running-on courses, any 40 character of knitting may be resorted to, the knitting of two yarns in a plating relation being only one of many ways in which knitting may be continued after the completion of the running-on courses. It is to be understood that the yarn A here disclosed as 45 withdrawn may be continued in action instead of substituting the yarn C.

As is clearly evident from Figs. 6 and 8, the upper yarn A is floated back of the low 50 needles. The taking of both yarns by the high needles 6 is indicated by four positions of one of the so-called high needles 6 in the diagram Fig. 9, and the taking of only one 55 yarn by the low needles 7 is indicated by four different positions of one of the so-called low needles 7 in that figure.

Having thus described one illustrative embodiment of the invention and the best mode 60 known to me for practising the method of the invention and producing the resulting fabric structure, it is to be understood that although specific terms are employed, they are used in a generic and descriptive sense and not for 65 purposes of limitation, the scope of the inven-

tion being set forth in the following claims.

Claims—

1. That method of commencing knitting upon bare needles which includes feeding two 70 yarns; causing all of the needles to take one of said yarns; causing certain of said needles, recurrent throughout the series, to take the other also of said yarns; causing said needles that take both said yarns to cast off the old loops in each course of a desired plurality of courses; causing those needles which take one yarn only to hold said taken yarn in each of a plurality of courses without casting off, and then to cast off the said yarn; and thereupon commencing regular knitting. 75

2. That method of commencing knitting upon bare needles, which includes feeding two yarns at substantially the same point; causing all the needles to take one of said 80 yarns; causing certain of said needles, recurrent throughout the series, to take the other also of said yarns; causing said needles that take both said yarns to cast off the old loops in each course of a desired plurality of courses; causing those needles which take one 85 yarn only to hold said taken yarn in each of a plurality of courses without casting off; and then to cast off said yarn whereby tuck stitches are formed; withdrawing that yarn that was taken by only certain needles; and 90 thereupon commencing regular knitting. 95

3. In a machine for commencing knitting upon bare needles, means to divide the needles into two groups of recurrent needles; means to feed at substantially the same point two yarns to all of said needles and one yarn only to one of said groups of needles; means for casting off the loops from that group of needles taking both yarns; means for causing the holding of the loops upon the other group of needles through a desired number of running-on courses, and means for causing the casting off as tuck stitches of all the loops of said second group of needles.

4. In mechanism for commencing knitting upon bare needles, a series of needles, jacks for recurrent needles only, means for causing said jacks to elevate their needles for the initial taking of the yarn, means to feed two yarns so that one group of bare needles takes one yarn only and the other group of bare needles takes both yarns, and means casting off both yarns by one group course by course and for casting off one yarn by the other group of needles in the form of tuck stitches at the end of a desired plurality of courses, whereby a desired plurality of running-on courses is provided.

5. In mechanism for commencing knitting on bare needles, a circular series of independent needles, jacks under alternate needles only, means for causing said jacks to elevate needles for the initial taking of yarn, means initially to feed two yarns so that one group of bare needles takes one of said yarns 125 130

only, and the other group of bare needles takes both of said yarns, and cooperating means whereby both yarns are cast off course by course at alternate needles, and both yarns are cast off at the remaining needles as tuck stitches at the end of a plurality of courses, whereby the desired plurality of running-on courses is provided.

6. In mechanism for commencing knitting on bare needles, a circular series of independent needles, jacks under alternate needles only, a jack cam to act upon said jacks, and means automatically to move said jack cams into and out of functioning position, means for causing said jacks to elevate needles for the initial taking of yarn, means initially to feed two yarns so that one group of bare needles takes one of said yarns only, and the other group of bare needles takes both of said yarns, and cooperating means whereby both yarns are cast off course by course at alternate needles, and both yarns are cast off at the remaining needles as tuck stitches at the end of a plurality of courses, whereby the desired plurality of running-on courses is provided.

7. In mechanism for commencing knitting upon bare needles, a circular series of independent needles, jacks for recurrent needles only, means for causing said jacks to elevate their needles for the initial taking of yarn, means initially to feed two yarns so that one group of bare needles takes one of said yarns only, and the other group of bare needles takes both of said yarns, and cam means for casting off both yarns at one group of needles course by course and for casting off one yarn at the other group of needles in the form of tuck stitches at the end of a desired plurality of courses, whereby the desired plurality of running-on courses is provided, and means for then commencing regular knitting.

In testimony whereof, we have signed our names to this specification.

ROBERT H. LAWSON.
ARTHUR N. CLOUTIER.
